SWIMMING INSTRUCTION APPARATUS

Joseph N. Borroughs, Piedmont, Calif.

Application April 18, 1945, Serial No. 588,965

6 Claims. (Cl. 272—71)

1

This invention relates to swimming instruction apparatus; the main object being to provide an apparatus, suitable for gymnasium installation, by means of which a person may be taught, or can practice, various swimming strokes, while in a swimming position and without the use of water.

Fig. 1 is a perspective view of the apparatus with a student in an operative position therein, so as to practice various swimming strokes on his own initiative, or under the tutelage of an instructor.

Fig. 2 is an end view of a supporting belt and roller unit.

Fig. 3 is a side elevation of the same.

Fig. 4 is a side view of one of the swivelly mounted hand-supporting frame units.

Fig. 5 is a transverse view of the same.

Fig. 6 is a top plan view thereof.

Fig. 7 is a fragmentary transverse view of the unit, showing different positions of the flexibly mounted hand-supporting glove.

Fig. 8 is a perspective plan of the frame unit, with a swimmer engaged therein.

Fig. 9 is a fragmentary perspective view of the body supporting belt.

Referring to the numerals of reference on the drawings, the apparatus comprises a main supporting frame which includes base members, standards 2 upstanding from members 1, and a top bar 3 connecting the standards. Standards 2 are spaced apart a distance greater than the height of any person.

Longitudinally spaced hanger-hooks 4 are supported by and depend from bar 3 intermediate its ends, these hooks disengageably supporting a bar 5. A rigid shaft 6 is supported by bar 5 a short distance below and parallel to the bar; the shaft supporting a pair of separate spools 7 which are turnable and slideable on the shaft. The spools in turn support separate flexible belts 8 adapted to surround the abdomen and hips of a student; the belts being split lengthwise and their split edges being detachably connected by lacing, hooks or other suitable means.

A short rigid stub shaft 9 projects rearwardly from the front standard 2, this shaft turnably supporting a light but rigid transverse rectangular frame 10 from the corners of which horizontal rods 11 project rearwardly.

Flexible cords 12 extend diagonally between the front and rear ends of the rods 11 on the same side; the cords radiating from and being connected to a ring 13 located in the plane of intersection of the cords. Gloves 14 are secured

2

in the rings in laterally projecting opposed relation to each other. The transverse spacing of the pairs of rods 11 and consequently the cords 12 and gloves 14 is such that the arms of a student whose hands are engaged in the gloves, will be substantially outstretched, as shown in Fig. 8.

A similar stub shaft 15 projects forwardly from the rear standard 2 on substantially the same level as the shaft 9; this shaft 15 turnably supporting a transverse frame 16. Rods 17 project forwardly from the corners of this frame and support diagonal flexible cords 18 from the point of intersection of which shoes 19 or similar foot receiving members project laterally out.

A rope 20 is secured on the rear end of bar 5 and extends upwardly to and about a pulley 21 on bar 3, and thence forwardly to and over another pulley 22 and downwardly to a termination to one side of frame 10.

If the apparatus is installed out in the open instead of a gymnasium, a tent 23 having a ventilating flue 24 may be placed over the apparatus.

To place himself in the apparatus, the student first removes bar 5 from hooks 4, and straps belts 8 loosely about his trunk or body. The forward end of bar 5 is then engaged with the front hook 4, and the rear end of the bar is then reengaged with the rear hook by pulling on rope 20.

The student then places his hands in gloves 14, and his feet in shoes 19. The student is thus disposed in a well-supported horizontal position and free to move the arms and legs thru different swimming strokes; the cords 12 and 18 being sufficiently slack to allow of a certain amount of lateral movement of the hands and feet, as indicated in Fig. 7.

If the student wishes to practice a side crawl, or a back stroke, he need only to twist his body in or with the belts, the rotatable mounting of the latter facilitating this operation as will be evident.

Since the frames 10 and 16 are freely turnable on horizontal axes substantially in alignment with the axis of belts 8, the student may also turn his arms and legs sideways, or to an inverted position, simultaneously with the corresponding turning movements of the body.

I claim:

1. A swimming instructive apparatus comprising a frame which includes spaced end standards, frame units supported from the standards in facing relation to each other for independent turning on a horizontal axis, transversely separated members on one unit to engage the hands of a

student in a swimming posture, similarly disposed members on the other unit to engage the feet of the student and means supported from the frame intermediate the frame units to support the body of the student.

2. A swimming instructive apparatus comprising a frame which includes spaced end standards, frame units supported from the standards in facing relation to each other for independent turning on a horizontal axis, transversely separated members on one unit to engage the hands of a student in a swimming posture, similarly disposed members on the other unit to engage the feet of the student and means supported from the frame intermediate the frame units to support the body of the student in which said means comprises a flexible body surrounding belt; with means mounting the belt for rotation about a horizontal axis above the body.

3. A swimming instruction apparatus comprising a frame which includes spaced end standards, frame units supported from the standards in facing relation to each other for independent turning on a horizontal axis, transversely separated members on one unit to engage the hands of a student in a swimming posture, similarly disposed members on the other unit to engage the feet of the student and means supported from the frame intermediate the frame units to support the body of the student in which said means comprises a relatively large-diameter body surrounding belt, a roller on which the belt is hung, and a horizontal shaft supported from the frame and on which the roller is turnable.

4. A swimming instruction apparatus comprising a frame which includes spaced end standards and a top bar connecting the standards; a body engaging belt, means detachably supporting the belt from the bar in a substantially horizontal position, and means associated with said bar adapted to raise said detachably supporting means into position; means supported from one standard to engage the hands of a belt-supported person in a swimming posture, and members supported from the other standard to engage the feet of the person while in such posture.

5. A swimming instruction apparatus comprising a frame which includes spaced end standards and a top bar connecting the standards; a body engaging belt, means detachably supporting the belt from the bar in a substantially horizontal position, members supported from one standard to engage the hands of a belt-supported person in a swimming posture, and members supported from the other standard to engage the feet of the person while in such posture with means mounting the members individually for limited lateral play.

6. A swimming instruction apparatus comprising a frame which includes spaced end standards, frame units supported from the standards in facing relation to each other for independent turning on a horizontal axis, transversely separated members on one unit to engage the hands of a student in a swimming posture, similarly disposed members on the other unit to engage the feet of the student and means supported from the frame intermediate the frame units to support the body of the student in which each frame unit comprises a rectangular transversely extending frame, the corresponding standard having a horizontal stub shaft on which the frame is turnable, rods projecting horizontally from the corners of the frame in a direction away from said standard, and flexible cords disposed in crossing relation and extending between opposite ends of the rods on each side of the frame, a rigid ring secured to the cords in the plane of their intersection; the corresponding members of said unit being mounted in the rings.

JOSEPH N. BORROUGHS.
